Application filed January 10, 1898. Serial No. 666,253. Term of patent 14 years.

To all whom it may concern:

Be it known that I, SILAS W. MASON, a citizen of the United States, residing at Amsterdam, in the county of Montgomery and State of New York, have invented a new and original Design for a Supporting-Bracket for Pails and the Like, of which the following is a specification.

This invention relates to a new and original design for a supporting-bracket for pails and the like; and it has for its object to provide a design of this character that shall be both useful and ornamental.

The leading feature of the design resides in a supporting-bracket having an arched arm with a fork portion at one end, the fork members being outwardly divergent and provided at their terminals with upturned hooks.

The minor features of the design are the arm, having at its inner end a flat rectangular plate, and in having the forked members compoundly curved.

In the drawings, Figure 1 is a perspective view of a supporting-bracket embodying the herein-described design. Fig. 2 is a front view of the bracket.

Referring to the drawings, the numeral 1 designates the main arm of the bracket, which is arched in a substantially inverted-U shape, and said arm is provided at one end with a fork 2, the fork members 3 being compoundly curved and provided at their terminals with curved upturned hooks 4.

The design is completed by a flat rectangular plate 5, arranged at the end of the arched arm 1, opposite the fork 2.

What is claimed is—

The design for a supporting-bracket for pails and the like, herein shown and described.

In testimony that I claim the foregoing as my own I have hereto affixed my signature in the presence of two witnesses.
